UNITED STATES PATENT OFFICE.

JENS E. ROHNE, OF MINNEAPOLIS, MINNESOTA, ASSIGNOR TO EVEN J. ROHNE, OF MINNEAPOLIS, MINNESOTA.

WATER HEATER FOR INTERNAL-COMBUSTION ENGINES.

Application filed June 21, 1926. Serial No. 117,376.

My invention provides an extremely simple and highly efficient water heater for internal combustion engines, especially adapted for use in connection with engines of motor-propelled vehicles. This heater is not only of simple construction, but is of such character that it may be quickly applied as a substitute for the customary coupling pipe used to connect the engine block to the radiator. For application of the invention to the engines of Ford cars, for example, the water-conducting pipe of the heater will be made of the same diameter and length as the standard Ford coupling pipe, so that the complete heater may be readily substituted for the removed coupling pipe. In the engines of certain other cars, a long flexible hose section is used as the coupling pipe, and in such arrangements, the heater may be readily substituted for such flexible hose coupling.

The heater is intended for what may be designated as "emergency" use, that is, for use in very cold weather to keep the cooling water of the engine in circulation and at such temperature far above the freezing point that the engine will start easily, even when the car is left in a very cold garage. The heater is designed to be readily coupled to any of the local wires of the lighting or heating system. A commercial form of the heater is illustrated in the accompanying drawings, wherein like characters indicate like parts throughout the several views.

Referring to the drawings:

Fig. 1 is a perspective diagrammatically showing an engine and radiator of the Ford type and illustrating the manner of applying the heater thereto;

Fig. 2 is a plan view of the heater, showing also portions of the flexible hose couplings connected thereto;

Fig. 3 is an axial section of the heater; and

Fig. 4 is a diagrammatic view illustrating the wiring of the heater.

Of the parts of the Ford car illustrated, the numeral 5 indicates the engine block and the numeral 6 the radiator. The numeral 7 indicates a cold water return nipple from the pan or base of the radiator, and the numeral 8 indicates the cold water return nipple applied in the usual way to the engine block. The numeral 9 indicates a hot water circulating connection between the top of the engine block and the top of the radiator.

In the usual Ford equipment, a metallic

coupling pipe is connected to the nipples 7 and 8, respectively, by short flexible hose sections 10 and 11. The heater designed for application to Ford cars comprises a main coupling tube 12, preferably of brass but of any other suitable metal, and which tube is of approximately the diameter and length of the removed coupling tube, not shown.

Surrounding the intermediate and main portion of the tube 12 is a cylindrical electrical heating element of such character that it is adapted to be telescopically slid as an entirety onto said tube. This heating element, as shown, comprises a heating coil 13 preferably wound on a very thin cylindrical core 14 of asbestos paper or the like. This coil is covered by a heavy surrounding jacket 15 of insulating material. The said members 13, 14 and 15 are cemented or otherwise connected together so that they form a self-contained unit adapted to be slid as an entirety onto the sleeve 12.

Loosely placed around this cylindrical heating element is a metallic sleeve 16 of considerably greater diameter and much shorter than the sleeve 12, and this outer sleeve, which constitutes a casing, is held in position spaced from and concentric with the heating element, by means of reducing collars 17 of aluminum, brass or other suitable metal. The larger inner ends of these collars 17 are telescoped over the ends of the outer sleeve 16, while the reduced outer ends of said collars closely fit the sleeve 12 and are securely anchored thereto against sliding movements, the latter noted action being preferably accomplished by interlocked bosses 18 pressed from the sleeve 12 into the said collars. The outer sleeve 16 is provided with outwardly projecting parallel contact pins 19 that are adapted for engagement with the imbedded contacts of a standard coupling socket 20 indicated by dotted lines in Fig. 3, and which socket is applied at the end of service wires 21 of the local lighting or heating system.

The contact pins 19 are shown as provided with nuts 22 located in the space between the outer sleeve 16 and the heating element. The ends of the heating wire 13 are coupled to the contact pins 19 and are formed with sufficient slack to permit this connection while the outer sleeve 16 is telescoped off from the heating element far enough to permit access to the nuts 22 for the purpose of effecting the connection just indicated.

The complete electrical heater made up of the various parts described, when assembled, is a very compact, simple and self-contained device capable of application to the engine of

- 5 a motor-propelled vehicle in the same manner that the customary or any suitable simple coupling pipe would be connected. This connection of the heater is accomplished by telescoping the ends of the sleeve 12 into the hose sections 10, then clamping the hose sections onto the same, preferably by the use of the ordinary clamping bands 23.

10 The efficiency of this heater has been thoroughly demonstrated in its use during the coldest winter weather, on the engines of automobiles in the open and in unheated garages. It may be quickly applied, quickly cut into and out of action and may be operated at very small cost.

- 15 20 This improved heater, it will be noted, does not in any way restrict the flow or circulation

of the water and, hence, when not in use, operates simply as a conducting pipe without obstructions and, therefore, is a perfect substitute for a removed standard coupling pipe. 25

What I claim is:

An electrical heater of the kind described comprising a coupling tube, a cylindrical heating element constructed as an entirety and telescoped onto the intermediate portion 30 of said tube, a relatively short outer cylindrical tube surrounding said cylindrical heating element, and reducing collars telescoped with the ends of said outer tube and having reduced portions closely engaging the inner 35 and relatively long tube, said heating element having contact pins projecting through said outer tube, the said parts being assembled as a self-contained unit adapted to be applied substantially as described. 40

In testimony whereof I affix my signature.
JENS E. ROHNE.
